GREETING CARD

Price Huber, Brookline, Mass., assignor to Rust
Craft Publishers, Inc., Boston, Mass., a cor-
poration of Massachusetts

Application January 22, 1938, Serial No. 186,385

3 Claims. (Cl. 46—34)

This invention relates to improvements in greeting cards and the general object of the invention is to provide a folded greeting card of novel and attractive appearance having complementary picture sections which, when the card is completely folded, will present a complete picture, and having means bearing a supplemental picture section operable when the card is partially or fully unfolded to present an elongated picture comprising one or more of the sections of the picture appearing on the card when completely folded.

The term "greeting card" is used herein in a broad sense as descriptive of any folded sheet or card presenting to the recipient of the card a suitable message, whether of greeting, congratulations, condolence, advertisement, or otherwise.

The term "picture" is also used in a broad sense as presenting an idea, whether by pictorial representation or by verbal presentation.

A further object of the invention is to provide a greeting card formed of an elongated sheet of suitable material having at one end a relatively narrow extension and having on the same side of the sheet and extension, picture sections so positioned that when the sheet is folded as hereinabove described the extension is passed through a slit in one of the leaves of the folded card and the card completely folded a complete picture is presented, and when the card is partially or wholly unfolded the supplemental picture on the extension will be so associated with other picture sections as to present a relatively long and different picture.

These and other objects and features of the invention will more fully appear from the following description and the accompanying drawings and will be particularly pointed out in the claims.

An illustrative embodiment of the invention is shown in the accompanying drawing, in which, Fig. 1 is a view of an extended sheet showing in dotted lines transverse fold lines and illustrating picture sections adapted, when the card is completely folded, to present one picture and when the card is opened to present a different and a relatively longer picture;

Fig. 2 is a view illustrating the opened card; and,

Fig. 3 is a view showing the card when completely folded.

The device as illustrated in Fig. 1 comprises an oblong or rectangular card having transverse fold lines 1, 2, 3, and 4, and at one end a relatively narrow extension 5 adapted when completely

folded to present a back leaf 6, main front leaf section 7 and an auxiliary front leaf section 8, and panels 9 and 10 at the ends of sections 7 and 8 respectively, with the extension 5 projecting from the end of the panel 10.

One of the picture sections 11 which, as illustrated, is a facetious representation of a cow boy carrying a lariat 12, is positioned on the main front leaf section 7 near the median fold line 1 with the rope extending to the upper end of a vertical slit 13 in the card. The auxiliary front leaf section 8 has upon it an illustration of the loop 14 of the lariat 12 which terminates at the fold line 4.

The panel 10 which is narrower than the panel 9, and extension 5 bear the representation of a bird in flight 15 carrying in its beak a greeting card 16 which is lassoed by the loop 14 of the lariat 13, the flying coil of the rope being shown on the extension 5.

In folding the sheet to produce the greeting card in opened form, as illustrated in Fig. 2, the sheet is first folded backwardly on the median line 1, so that the main front leaf section 7 and its panel 9 are in the same plane and preferably extend to the fold line 4. The panel 10 is then folded backwardly on the line 4 over the panel 9 and the end of the extension 5 inserted through the slit 13. This produces an elongated complete picture showing the facetious cow boy lassoing the card which is carried by the bird in flight.

A fold line 17 for the extension is provided at the junction of the extension with the end of the narrow panel 10.

In order to produce the smaller complete picture illustrated in Fig. 3, the panel 9 of the main front leaf section and the panel 8 of the auxiliary front leaf section are folded forwardly on the fold lines 2, 3, the narrow panel 10 and its extension being folded beneath the panels 8 and 9 as illustrated in Fig. 3. When thus folded the extension 5 is bent on the fold line 17 so that the extension is thrust to the right through the slit further beneath the main front leaf section 7, as illustrated in dotted lines in Fig. 3. When thus folded the looped end of the lariat on the front leaf section 8 is brought into a position in which the section of the rope 12 unites with the section 12 of the rope which extends from the hand of the cow boy thereby completing the narrow picture.

When the card is completely folded, as illustrated in Fig. 3, a complete picture of the facetious cow boy is shown as swinging the lariat to produce the loop. When the card is opened another complete picture is shown illustrating the cow boy

after having cast the loop about the card which is carried by the bird in flight.

The greeting card as constructed may have printed upon it suitable messages for the recipient one of which is shown in the drawing.

Obviously various other sectional pictures may be shown, for example, the panel 7 and 8 may, when the card is folded, illustrate a birthday cake partially appearing upon each of the complementary front leaf sections with a figure on one of the front leaf sections of a child cutting the cake and figures on the other front leaf section of those waiting to participate in eating the cake. In extended form the illustrations on the front leaf 7, the extension 5, and the panel 10, may show an enlarged cake, with various figures surrounding it.

In another form the folded card may illustrate a bassinet containing a baby with figures such as a child or children or animals admiring the baby and when in elongated form a much larger bassinet containing a series of babies appearing upon the extension with the panel 10 together with the illustration on the front page completing the illustration of the bassinet. Such modifications of the illustration may be made indefinitely by reason of the construction above described.

It is to be noted that in each instance all of the figure sections may be printed simultaneously upon the same side of the card thereby reducing the cost of printing to a minimum.

It will be understood that such cards may be printed with suitable verbal messages as well as pictorial which when the card is completely folded will present one thought and when the card is opened present a different or supplemental message.

It will therefore be understood that the particular embodiment of the invention shown in the accompanying drawing is of an illustrative character and not restrictive of the meaning and scope of the following claims.

Having thus described the invention, what is claimed as new, and desired to be secured by Letters Patent, is:

1. A greeting card comprising a sheet folded to provide a back leaf and cooperating front leaf sections bearing complementary picture sections normally presenting a complete picture when the

card is completely folded, a folded panel extending from one of the front leaf sections having a relatively narrow extension projecting from the side of said panel into a slit in the other front leaf section and containing a supplementary picture section operable upon unfolding the card to be partially withdrawn from said slit and to produce with one or more of said complementary picture sections a different, complete and relatively longer picture.

2. A greeting card comprising a folded sheet having a back leaf and front leaf sections folded thereupon bearing complementary picture sections normally presenting a complete picture when the card is completely folded, a folded panel extending from one of the front leaf sections and having a relatively narrow extension projecting from the side thereof into a slit in the other front leaf section, said panel and extension containing a supplementary picture section operable upon unfolding of the front section of the card partially to withdraw the extension from said slit and to produce a complete, longer and different picture, all of the picture sections being printed on the same side of the unfolded sheet.

3. A greeting card comprising a sheet having transverse fold lines to provide a back leaf, a main front leaf section and an auxiliary front leaf section, the main front leaf section having an end panel defined by a transverse fold line which when the main front leaf section and its panel are folded against the back leaf will be substantially co-extensive therewith, a relatively narrow panel on the end of the auxiliary front leaf section defined by a fold line, a narrow extension projecting centrally from the edge of said narrow panel with the fold line at its junction therewith and extending when said narrow panel is folded over the panel of the main front leaf section through a slit in the main front leaf section, a main picture section on the main front leaf, and a complementary picture section on said auxiliary front leaf forming therewith a complete picture when the card is completely folded and a different complementary picture section on said narrow panel and its extension forming with the picture on the main leaf a different longer picture when the card is unfolded.
